UNITED STATES PATENT OFFICE.

J. EDWARD BICKNELL, OF CLEVELAND, OHIO.

APPARATUS FOR THE MANUFACTURE OF GAS.

SPECIFICATION forming part of Letters Patent No. 284,801, dated September 11, 1883.

Application filed March 2, 1883. (No model.)

To all whom it may concern:

Be it known that I, J. EDWARD BICKNELL, of Cleveland, in the county of Cuyahoga and State of Ohio, have invented a new and Improved Apparatus for the Manufacture of Illuminating-Gas, of which the following is a full, clear, and exact description.

The object of my invention is the manufacture of a fixed gas of high illuminating-power by the mixture of gas produced by the distillation of wood and the decomposition of liquid hydrocarbon at a nominal cost; and to that end I make use of sawdust for production of the wood-gas, and heat the liquid hydrocarbon, so as to obtain the vapor under pressure sufficient to force it into the mixing-chamber. I also make use of an apparatus constructed to permit the rapid and continuous distillation of the wood-gas, and thereby save the labor and expense of stopping the work for charging and cleaning the retorts, all as specified more particularly hereinafter.

Reference is to be had to the accompanying drawings, forming a part of this specification, in which similar letters of reference indicate corresponding parts in all the figures.

Figure 1 is a sectional elevation of my improved apparatus. Fig. 2 is a plan view of a part of the same. Fig. 3 is a perspective view of the wood-retort detached from the brick-work and with the cover removed. Fig. 4 is a longitudinal section of the superheater, and Fig. 5 a detail view of the injector.

The wood-retort A consists of a circular pan set in the brick-work of a furnace, B, and provided with a suitable cover. At the center of the retort is a shaft, a, carrying rakes or scrapers b b. At c, in the bottom of the retort, is an opening above a discharge-spout, d, the lower end of which enters a water-box, e, by which the opening is sealed; or, if preferred, the spout may be sealed by an air-tight chamber. At f, above the retort, is a feed-chute opening into the retort A and provided with a hopper, g. In the chute, below the hopper, is a piston, h, fitted for reciprocation, so as to force the sawdust to the retort.

C is a superheating-chamber for containing charcoal, as shown in the section, Fig. 4, and D is a second superheater, both heated by the same furnace.

i is a pipe from one end of chamber C to the

stand-pipe k of retort A. l is a pipe from the opposite end of chamber C, connected to a T-pipe, m, that enters the superheater D.

55

E is an oil-retort, heated by a separate furnace, and connected by a pipe, n, to the T-pipe m, entering the T in the manner of an injector, and terminating in a rose-jet. The retort E is provided with gages for indicating the height 60 of the oil and pressure of the vapor. From superheater D a pipe, o, leads to a hydraulic main, p, and condenser q.

In the operation of the apparatus the sawdust is fed to retort A by the feeder, the chute 65 f being full at all times to prevent escape of gas. The sawdust falling upon the bottom of the retort is spread by the rakes, that are to be revolved by power applied to the shaft, and the retort-bottom being red-hot, the sawdust is 70 almost instantly converted into charcoal, and the gas, pyroligneous acid, and tar-vapors driven off. The charcoal is carried by the scraper to opening c and discharged, and fresh sawdust being constantly supplied, the operation 75 is thus continuous, and there is no accumulation of charcoal on the retort-bottom to hinder the rapid carbonization of the wood.

The gaseous products pass to the superheater C, in which is charcoal heated to incandescence. They pass through this incandescent charcoal and are converted into carbonic oxide. Thence they find their way through T-pipe m into the mixing-retort D. Simultaneously with these operations the oil-retort E is heated, 80 a valve in pipe n being kept shut until the vapors are at the required pressure. The valve is then opened and the heavy vapors are forced by the pressure into pipe n and the superheater D in the form of spray. The wood-gas 90 and the hydrocarbon vapor unite in the superheater D, where they are converted to a fixed gas of high illuminating-power. This gas then goes to the purifier and the condenser, although very little purification is necessary. 95 The products of condensation are drawn off by pipe r from the condenser q.

With this apparatus and process illuminating-gas of high power can be produced in large quantities at slight cost. The sawdust, being 100 a waste product, is inexpensive, and can be converted with but little heat, compared with wood in blocks. The charcoal being removed as fast as made, there is no waste of heat, and

a larger amount of gas can be produced from a given weight of sawdust than from the same weight of wood in blocks. Further, the operation is continuous, as the wood-retort is automatically charged and cleaned without stopping the operation of gas-making, thus saving a large amount of time, labor, and expense of extra firing, and preventing the usual waste of gas during the charging operation. By heating the hydrocarbon and introducing the vapors into the superheater under the pressure obtained by the heating, a thorough mixture with the wood-gas is insured and without the use of steam for the purpose. The pressure is greater than can be obtained by the introduction of steam. The spraying is consequently more minute, and the deterioration of the illuminating-power of the vapors by the steam is avoided, so that less hydrocarbon is required to enrich the wood-gas to a proper standard.

I am aware that it is not new to vaporize hydrocarbon and distill wood in separate retorts, and to afterward combine the products

in a third retort; but by the arrangements used it has been difficult to properly regulate the supply of hydrocarbon vapor, and when steam is used it is open to the objections before named. I am also aware it is not new to use a superheating-retort containing charcoal heated to incandescence.

Having thus fully described my invention, I claim as new and desire to secure by Letters Patent—

1. The combination, with the retort A, having the bottom aperture, c, of the rotary shaft a; carrying radial rakes b, adapted to spread the sawdust and transfer the charcoal to the discharge c, as described.

2. The apparatus for making illuminating-40 gas, consisting of wood-retort A, superheaters C D, oil-retort E, and connections l m n, substantially as shown and described.

J. EDWARD BICKNELL.
